UNITED STATES PATENT OFFICE.

WILFRED E. TAIT, OF BOSTON, MASSACHUSETTS, ASSIGNOR TO HAROLD J. CLARK, OF BOSTON, MASSACHUSETTS.

PERMUTATION LOCK FOR SAVINGS BANKS.

Application filed December 17, 1926. Serial No. 155,474.

My present invention relates to permutation locks for savings banks.

A principal object of my present invention is to provide a small, compact, portable savings bank, the exterior casing of which will comprise the operating means for the locking instrumentalities.

A further object of the invention is to provide a bank which it will be impossible to open except by the person knowing the combination, whereby the locking means may be released and the bank opened.

A still further object is the provision of such a bank which will be economical of manufacture, simple of assembly, and positive in operation.

Another object of my invention is to provide automatic means which will prevent the escape of money through the entrance provided therefor, and thus prevent pilfering from the bank until such time as the person controlling the same desires to open it.

It will be appreciated that by having its locking means controlled by means of a combination is much safer and more difficult to open than one which is controlled by a key or other means. I have, therefore, devised my present bank with a lock of a permutation type, so that it can be utilized in a great many ways. For example, savings banks could issue these small portable banks to depositors, the bank retaining the combination, the depositor to return the same to the bank when full, and the bank would then open the small portable bank by means of the combination, credit the amount to the depositor's account, and return the same bank to the depositor. Or a parent could give these banks to children, the parent retaining the combination, so that the bank could not be opened or money obtained therefrom without the consent of the parent.

I have also devised a bank which is easy to operate, when the combination is known, small and compact, attractive in appearance, and at the same time is a very useful article.

Further objects of the invention, novel combinations of parts, details and advantages, will be herein more fully pointed out and claimed.

Referring to the drawings, illustrating a preferred embodiment of my invention,

Fig. 1 is a side view of my completed bank in closed position;

Fig. 2 is a cross sectional view illustrating the bank in position ready to be opened;

Fig. 3 is a top plan view;

Fig. 4 is a cross sectional view illustrating the notches and locking lugs in alignment, ready to be opened;

Fig. 5 is a cross sectional view of the locking portion of the bank in fully locked position;

Fig. 6 is a cross sectional view illustrating the notches in alignment with the locking lugs out of alignment;

Fig. 7 is a cross sectional view illustrating my novel automatic means for preventing the escape of money through the entrance; and

Fig. 8 is a fragmentary cross sectional view in enlarged detail of the locking lugs and notches or recesses aligned to permit opening.

As shown in the drawings, my novel bank is constructed of an outer casing, comprising two portions or members 1 and 2, the portion 1 having thereon a combination dial arrangement with the letters A, B, C, etc., with corresponding notches or indications for each letter, and the lower member 2 has thereon an arrow 3 adapted upon rotation of either member to be aligned with any predetermined letter of the combination. Each member 1 and 2 is provided with knurled portions 4, 4, to afford gripping means and facilitate rotation of the casing members. Secured to the casing member 1 by rivets 5 is a cylindrical sleeve 6 having at its lower portion a flange or shoulder 7, to which flange or shoulder are secured locking rivets or lugs 8. A projection or alining lug 9 is also formed, preferably as an integral part of the flange 7. Secured, preferably by a pressed fit in the extreme lower portion of the casing member 2 is a ring or sleeve 10, having therein a plurality of notches 11, here illustrated as three in number. This sleeve or ring 10 is press fitted into the casing member 2, in such manner as to prohibit rotation thereof. A disc or plate 12 is rotatably secured to the bottom of the casing member 2 by a rivet 13, which rivet also engages a plate or disc 14. The plate or disc 14 is preferably of spring metal, and formed concave, exerting downward spring tension on the disc 12, so that

the disc 12 may be rotated, but only upon the application of pressure or force. The disc 12 has formed therein notches 15, here shown as three in number, and corresponding to the notches 11. It will be noted that the distance between each of the notches 11, each of the notches 15, and the locking rivets 8 is different. Thus, until the notches 11, 15, and rivets 8 are alined, as clearly shown in Fig. 4, the component parts of the bank will be held in rigid, positive, locked position.

In the top of the bank I have provided the customary coin entrance or slot 16. Within the bank, and preferably secured thereto by a press fit is a member 17 having a slot 18 alined with the slot 16. Grooves 19 are provided at each end of the member 17, and a rod 20, preferably cylindrical, is free to slide vertically, in said slots or grooves 19. Thus, when the rod 20 is in the position illustrated in Fig. 2, the entrance of money may be effected. On reversing the position of the bank, however, viz, tipping it upside down to extract money therefrom, the rod 20 will slide in the grooves 19, effectually blocking the slots 18 and 16, and preventing the removal of money from the bank.

The operation of my novel bank is simple, and will be readily understood.

Assuming it to be desired to open the bank for any purpose, either portion 1 or 2 may be rotated. Preferably, however, the upper portion 1 is held, with the first letter of the combination to be dealt with facing the operator, and the lower portion is rotated one or more turns to the right, until the arrow 3 is in alinement with the indication for the letter with which it is to be alined, in this instance it is the letter "P", which is not shown on the drawing Fig. 1. During this rotation, the lug 9 engages a lug 21 on the disc or plate 12, rotating the said disc or plate against the tension of the spring 14 until the arrow has alined with the desired letter, viz, P. When the arrow 3 engages with the letter P the grooves 11 and 15 are in alinement, as illustrated in Fig. 6. The locking rivets 8, however, are out of alinement with the alined grooves. Thereupon rotation of the casing member 2 to the left, until the arrow 3 is alined with the next appropriate letter, as in this instance E, the locking rivets 8 will then be alined with the notches 11 and 15, as shown in Fig. 4, whereupon the casing parts 1 and 2 may be separated, money withdrawn, and the parts replaced. On rotating the casing member 2 to the second letter, the lug 21 is disengaged from the lug 9 leaving the notches 11 and 15 in alinement, as will be readily appreciated from a glance at the drawings.

When the parts are replaced, viz, with the letter E in alinement with the arrow 3, the locking rivets will again enter between the

notches 11 and 15, and thereupon rotation of the casing 2 past the letter P will again disaline the notches 11 and 15 and the locking rivets 8, and the bank is then in locked position, as clearly shown in Fig. 5, and rendering it impossible to open the bank until further manipulation of the correct combination.

By providing the spring means 14, the disc or plate 12 is always held under equal tension, and cannot rotate except upon engagement of the lug 21 with the lug 9, or vice versa.

The operation of my novel bank, from the operator's standpoint will be readily understood, and will be very simple to carry out. For example, the purchaser buys the bank with the combination letters "P", "E", or any other pair of letters adapted to operate the combination, he deposits a desired amount of money in the bank, and when it is desired to withdraw the same, takes the member 1 in one hand and the member 2 in the other hand, rotates the member 2 two complete revolutions to the right, stopping at the letter P, then reverses the rotation of the member 2 until the letter E is in alinement with the arrow 3, whereupon the two members 1 and 2 may be separated from each other, permitting ready withdrawal of the contents of the bank. He thereupon closes the same by pressing the members 1 and 2 together and revolves the member 2 in either direction, thus disalining the locking instrumentalities and locking the bank until it is desired to open same.

While I have necessarily described my present invention somewhat in detail, it will be appreciated that I may vary the size, shape, and arrangement of parts, within reasonably wide limits without departing from the spirit of the invention.

My invention is further described and defined in the form of claims as follows:

1. A device of the kind described, comprising a pair of rotatable casing members, a sleeve affixed to one of said casing members, locking rivets on said sleeve, a ring affixed in the other casing member and having notches therein, a rotatable spring pressed plate secured to said other casing member and having notches therein, means operable upon rotation of one of said casing members to bring the notches in said ring and plate into alinement, to permit passage of the locking rivets through said notches, and separation of said casing members.

2. A device of the kind described, comprising a pair of rotatable casing members, a sleeve affixed to one of said casing members, locking rivets on said sleeve, a fixed lug on said sleeve, a ring affixed in the other casing member and having notches therein, a rotatable spring pressed plate secured to said other casing member and having notches

therein, a lug on said plate, said lugs engaging on rotation of one of said casing members to a predetermined position to bring said notches into alinement, to permit passage of said locking rivets through said notches upon rotation of said casing member to a second predetermined position.

3. A device of the kind described, comprising a pair of rotatable casing members, 10 a sleeve affixed to the interior of one of said members, an inturned flange at the bottom of said sleeve, locking rivets affixed to and depending from said flange, a lug projecting inwardly from said flange, a flanged 15 ring affixed in the other casing member and having notches therein, a rotatable spring

pressed plate secured to said other casing member and having notches therein, an upturned lug on said plate, said lugs being adapted to engage, on rotation of one of 20 said casing members to a predetermined position, to bring said notches into alinement, said locking rivets being adapted to be brought into alinement with said alined notches upon rotation of said casing member 25 to a second predetermined position, to permit passage of said rivets through said notches.

In testimony whereof, I have signed my name to this specification.

WILFRED E. TAIT.
